UNITED STATES PATENT OFFICE

2,370,927

CONTAINER COVER AND ATTACHMENT
THEREFORRoy D. Anderson, Lawrence, Kans., assignor to
Lawrence Paper Company, Lawrence, Kans., a
corporation of Kansas

Application December 14, 1942, Serial No. 468,948

2 Claims. (Cl. 229—45)

This invention relates to covers for containers, preferably of a general character disclosed, for example, in Patents No. 1,774,511 of September 2, 1930, issued to Irving Hill et al., and No. 2,288,707 of July 7, 1942, issued to Irving Hill, and more particularly to an arrangement for applying covers to containers.

The principal objects of the invention are to provide a convenient, efficient and economical cover together with related devices for facilitating attaching the cover to and securing same to a container; to provide for easily detaching the cover or a part thereof from a container to inspect the contents of or remove said cover from the container for re-use or other purposes; to provide integral means on the cover for securing same to a container; to provide a cover and a container structure which may be closed without the use of tape, stitching or metal fasteners; to provide a container cover capable of being knocked down before or after use and shipped flat to a point of use; to provide access to the locking device of the cover for releasing same; to provide locking members on the cover which are held in place by contact with the container; and to provide improved elements and arrangements thereof in container covers of the character and for the purposes set forth.

In accomplishing these and other objects of the present invention, I have provided improved details of structure, the preferred forms of which are illustrated in the accompanying drawing, wherein:

Fig. 1 is a perspective view of a container to which a cover is attached in accordance with the present invention.

Fig. 2 is a fragmentary plan view of a blank from which the preferred form of cover is constructed.

Fig. 3 is a fragmentary perspective view of a container showing a cover therefor embodying my invention in spaced relation thereto.

Fig. 4 is a detail vertical cross-section substantially on the line 4—4, Fig. 1.

Fig. 5 is a detail horizontal cross-section through the end of a container and cover illustrated in Fig. 1 substantially on the line 5—5, thereof, particularly illustrating the tongue lock.

Fig. 6 is a detail horizontal cross-section through a corner of the container and cover, particularly illustrating a modified arrangement of the locking tongue.

Referring more in detail to the drawing:

1 designates a container, which is preferably of the general type disclosed in the patents above

mentioned, and which preferably includes a bottom wall 2, side walls 3 and 4 and end walls 5 and 6, side flaps 7 and 8 being provided on the upper edges of the side walls if desired. The upper edges of the end walls of the container are preferably provided with flanges 9 and 10, which may be folded outwardly and downwardly to form hook or like members.

11 designates a cover, preferably of substantially the same size, shape and material as the container, the cover constituting a body member preferably having inner end flanges 12 and 13 foldable over the container end wall flanges. The flanges 12 and 13 have fold lines 14 and 15 spaced from the end edges of the cover member to form outer end flanges 16 and 17 and adapt the flanges for folding under and/or behind the container flanges 9 and 10. The cover end flanges thus, in effect, form hook or like members interengagable with the container hook members for applying the cover in closing relation to the container.

In order to aid in maintaining the container and cover hook members in interengaged relation and to further enhance confinement of the contents of the container, the cover 11 is preferably provided with side flanges 18 and 19 which are foldable over the upper edges of the side walls of the container.

The side flanges of the cover have tabs 20 and 21 that fold on score lines 22 and 23 adjacent the corners of the container to overlap the cover end flanges 12 and 13. It has been found desirable to provide spaced slots 24 and 25 in the end flanges of the cover which slots are preferably of a length to extend substantially the full width of the inner end flanges 12 and 13 so that tongue extensions 26 and 27 of the tabs 20 and 21 may be applied to and extend through said slots to positively lock the flanges and tabs of the cover and container in interengaged relation.

In order to additionally secure the flanges and lock the tongue extensions in place, the tabs 20 and 21 are preferably provided with score lines 28 and 29 making said tabs of substantially the same length as the spacing of the slots 24 and 25 from the sides of the cover. The tongues 26 and 27 extending through the slots 24 and 25 may then be folded backwardly on the score lines 28 and 29 as at 30 against the interior face 31 of the end flanges 12 and 13. There is a tendency for the elements and tabs of the cover to return to blank or flattened form. This tendency is used to advantage in such a manner that when folded and applied as shown, the cover flanges, tabs and tongues frictionally engage each other and the

container flanges for producing considerable resistance to change, thereby holding the respective parts in interengaged and locking condition.

Removal of the cover from the container to which it is applied is preferably facilitated by providing the end flanges 12 and 13 with apertures 32 to permit passage of a finger or other object to engage the container end flanges 9 and 10 and release same from engagement with the cover outer end flanges 16 and 17 to permit lifting of the cover from said container, one end preferably being disengaged at a time.

In attaching a cover to a container both of which are constructed as described, the side and end flaps of the cover member are folded downwardly and the tabs 20 and 21 on one end of said cover are preferably folded over the end flange 13 and the tongues 26 and 27 are applied to and extended through the apertures 24 and 25 in said end flange, said tongues 26 and 27 preferably being folded over and behind the cover flange 13. This end of the cover may then be applied to one end of the container and the outer flange 17 is folded upwardly and inwardly to engage under or behind the flange 10 of the container. The container side flaps being folded inwardly, the other end of the cover may then be lowered to cover the open upper end of said container. The side flaps of the cover fit over the upper outer edges of the container side walls.

The end flange 12 of the cover is folded downwardly and the outer end flange 16 thereof folded inwardly and upwardly to engage under or behind the container flange 9. The tabs 20 and 21 are then preferably folded to overlie the end flange 12 and the tongues 26 and 27 are inserted in slots 24 and 25 and folded backwardly over the inner face of said end flange 12 in such a manner that it lies between said end flanges 12 and 16 and is engaged with the outer face of the container end flange 9. The tendency of the elements to return to flat condition causes the end flanges 9 and 10 to exert pressure outwardly to hold the tongues 26 and 27 in engagement with the inner face of the cover end flanges 12 and 13. In the same manner, the tongues 26 and 27 exert pressure on the flanges 16 and 17 and 9 and 10 to hold same in alignment and substantial engagement with the ends 5 and 6 of the container.

In order to release the cover from the container, a finger or other object is inserted through the aperture 32 to press the flanges 9 and 10 toward the ends of the container. Simultaneously, the lower edges of the cover flanges 16 and 17 are grasped and drawn outwardly to cause disengagement between the flanges 9 and 16 and 10 and 17. Preferably, one end of the cover at a time is released from the container to provide more room for releasing the engaged flanges and permit more facile removal of said cover.

The form of the invention shown in Fig. 6 is of the same construction as that shown in the preferred form with the exception that the tabs 20 and 21 are not provided with the score lines 28 and 29. The tongue extensions extend through the slots 24 and 25 and lie against the inner face of the flange 12. The same general tendency for the flanges of the cover to flatten

out is present in this form and the frictional reaction is substantially the same to maintain the elements of the cover in engaged condition. After the cover has been removed from the container and the contents thereof emptied, the flanges 16 and 17 may be straightened to permit removal of the tongues 26 and 27 from the apertures 24 and 25 and to also permit the entire cover structure to be opened and laid out in flat form for shipment to a point of re-use. Since there are no tapes, staples or metal fastening devices used, the structure of the cover is not damaged and can be used many times.

It is apparent therefore that a convenient, economical and efficient arrangement is provided by the present invention for attaching or detaching a cover wholly or in part to a container and when detached, said cover may be knocked down and shipped to a point of re-use without damage to said cover. The cover and container also have numerous advantageous characteristics, among which are exceptional strength, durability and security for contents in the container.

What I claim and desire to secure by Letters Patent is:

1. In a device of the character described, a container having outwardly and downwardly turned flaps on the end walls thereof, a cover for the container having downwardly turned flaps on the sides and ends thereof, said downwardly turned flaps on said ends of the cover having apertures therein adjacent the ends thereof and being provided with a fold line and upwardly extending flap portions on the outer edge of said downwardly turned end flaps, said upwardly extending flap portions being adapted to fold over and lockingly engage said end flaps on the container in edge abutting relation, tabs on the ends of the downwardly turned flaps on the side flaps of the cover foldable over the downwardly turned flaps on the ends of said cover, tongues on said tabs insertable in the apertures in the adjacent end flaps and foldable backwardly against said end flaps to secure the respective flaps in locking position, the end portion of said tongues having engagement with the downwardly turned flaps on the container to maintain said container flaps and the upwardly extending flap portion on the outer edge of the downwardly turned end flaps in edge abutting engagement to hold the cover on the container.

2. A container having side walls and reversely turned flanges on selected side walls, a cover for the container having flanges adapted to engage over the side walls of the container, selected flanges on said cover being provided with reversely turned flanges adapted to abut the edges of the reversely turned flanges on the container, said selected flanges on the cover being spaced from the reversely turned flanges on the container, and tongues on the side flanges of the cover projectable between said selected flanges on the cover and the reversely turned flanges on the container for locking said reversely turned flanges in engagement to anchor the cover on the container.

ROY D. ANDERSON.
